CANNON BANK

James Wilson Craighead, 3120 Blake St.,
Denver, Colo. 80205

Filed June 20, 1966, Ser. No. 2,734

Term of patent 3½ years
(Cl. D34—11)

The dominant features of my design reside in the full line portions and is characterized by the combination of the cannon base configuration and the particular wrap-around holder for the bottle, all as shown.

I claim:

The ornamental design for a cannon bank, as shown and described.
